PRODUCTION OF DIENES

Rupert C. Morris and Robert J. Moore, Berkeley, Calif., assignors to Shell Development Company, San Francisco, Calif., a corporation of Delaware

Application June 15, 1942, Serial No. 447,139

3 Claims. (Cl. 260—680)

This invention relates to the art of cracking hydrocarbons and more especially to the manufacture of diolefines and other valuable products by vapor phase cracking of especially selected and prepared feeds.

Diolefines, and especially butadiene and isoprene are useful as starting materials in the manufacture of elastomers; that is, polymeric materials which have elastic properties similar to rubber, and find successful applications in different arts. Elastomers may be produced either by polymerizing a diolefine alone or by copolymerizing diolefines and other unsaturates.

The behavior of different dienes is often similar but, as could be expected, marked differences in conditions required for polymerization or copolymerization, or in properties of the resulting products, may be caused by variations of molecular weight and structure.

Each diene has its own characteristics which make it superior for certain uses and inferior for others. Thus, for example, rubber-like products formed by copolymerizing styrene with butadiene are harder than those obtained by copolymerizing it with isoprene and thus less adapted to some purposes.

It is well known to prepare dienes by dehydrogenation of corresponding olefines, by dehalogenation or dehydrohalogenation of corresponding halogen derivatives, dehydration of corresponding alcohols, etc. These methods, however, besides having certain other disadvantages, as for example the cost involved in preparing the starting materials, allow only the production of one kind of diene from one starting material.

It is also known that cracking of hydrocarbons often yields minor proportions of various dienes, particularly of butadiene. The proportion of the diene in the cracked products is, however, small, and it is associated with major amounts of saturated and ethylenic hydrocarbons having nearly equal vapor pressures. Thus, their recovery is difficult and their yields are small.

Certain selected hydrocarbon feeds yield, upon cracking under particular conditions, relatively large proportions of dienes and relatively diene-rich fractions from which these hydrocarbons may be recovered more economically. Here again, however, only one diene or several dienes only in one given proportion may be obtained from one feed.

Thus by cracking normally liquid normal monoolefines in the vapor phase at temperatures above 600° C., gases may be obtained which contain substantial amounts of butadiene, and selected narrow boiling fractions of such gases may comprise almost 50% of this gas. Pentadiene is simultaneously produced in smaller amounts.

Varying the conventional cracking conditions such as temperature, pressure, residence time, etc.,

may greatly change the yields of, and conversion per pass to, these dienes but fails to alter appreciably their relative proportion in the cracked products.

5 It is an object of this invention to provide a process for the manufacture of valuable hydrocarbons, especially dienes and particularly pentadienes, by treating and cracking a selected hydrocarbon stock which is readily available.

10 Another object is to provide a practical method for varying the composition of dienes produced from a hydrocarbon feed by cracking and particularly for varying the relative proportion of buta- and pentadienes.

15 Another object is to produce hydrocarbon fractions rich in di- and mono-olefines and aromatics from which these valuable hydrocarbons can be separated in a simple manner. Still further objects include simplified procedures, decreased cost in the manufacture of dienes, and other improvements found hereinafter.

20 This invention is based on the discovery that the nature of the cracked products obtained by cracking normal hydrocarbons and particularly normal mono-olefines may be radically changed if the feed is subjected to an isomerization prior to cracking. Thus, while dienes obtained from unisomerized wax olefines comprise mainly butadiene, those obtained therefrom after isomerization predominate in pentadienes.

25 30 According to one aspect of this invention, normally liquid normal mono-olefines are subjected to isomerization and thereafter cracked in the vapor phase at a temperature above about 600° C. to yield pentadiene.

35 According to another aspect of this invention, a varying proportion of the feed is subjected to isomerization, or a constant proportion is isomerized to a varying degree prior to cracking and the nature of diolefines in the cracked products 40 is thereby regulated.

45 Still further features of this invention deal with the recovery of the valuable hydrocarbons which are thus obtained, and particularly the recycle of certain fractions thereof, and also with a system wherein this process may be performed.

50 Normal mono-olefines having a chain length between 6 and 12 carbon atoms are preferred for practicing this invention, giving particularly high yields of dienes. Such normal mono-olefines may be produced by any suitable method, and most conveniently by the Van Peski process described in U. S. Patent No. 2,172,228, according to 55 which normally solid paraffin wax or highly paraffinic distillates predominating in crystallizable paraffins are cracked in the vapor phase at temperatures below 600° C. Especially large yields of such paraffin are obtained by subjecting these hydrocarbons in the presence of steam to temperatures of 540° C. to 570° C. and pressures below

75 p. s. i. for a time period from 3 to 6 seconds, and quenching the cracked products. Distillates obtained therefrom, boiling under 300° C. predominate in normal mono-olefines and are very suitable for use as cracking stocks of this invention, particularly the distillates boiling from about 60° C. to 210° C.

Other sources of normal olefines include, for example, the dehydration of normal alcohols obtained by reduction of naturally occurring normal fatty acids, dehydrohalogenation of mono halogenated normal paraffins, etc. These methods are however, in general less practical than cracking of paraffin wax as described.

The isomerization step of this process is preferably conducted under conditions favoring a change in the structure of normal olefins, i. e. migration of the ethylenic linkage and especially branching of the hydrocarbon chain without substantial dehydrogenation, cracking or polymerization of the molecules, i. e. substantially without change of their molecular weights or empirical formulae. Variations in temperature and pressure alone are in general unable to provide such conditions and the presence of a catalyst is required.

Suitable isomerization catalysts are well known in the art and include, for example, activated alumina, e. g., bauxite which has been dehydrated; alumina which has been heated to about 400° C. to 700° C. and washed with acid; ion exchange agents such as hydrated aluminum silicates, particularly zeolites and permutites such as are more fully described in U. S. Patent No. 2,175,252 to Han Hoog; many so-called cracking catalysts comprising oxides such as silica, alumina, magnesia, zirconia, thoria, many polymerization catalysts such as so-called solid phosphoric acid catalysts, etc. Suitable commercial catalysts include, for example, "Porocel," "Doucil," "Nalco No. 300" catalyst, etc.

The conditions of isomerization—that is, temperature, pressure and contact time, vary greatly with the nature of the catalyst used. Temperatures in the range of 250° C. to 500° C. are often suitable. Low temperatures in general cause the isomerization to proceed slowly, while high temperatures tend to cause dehydrogenation or cracking or polymerization or several of these undesirable side reactions. Suitable pressures are in general of the order of atmospheric or moderately above, for example, 7 to 100 p. s. i. absolute. Low pressures necessitate larger volumes of catalyst and apparatus for a given contact time, high pressures favor undesirable polymerization. Contact time depends greatly on temperature and the nature of the catalyst, and may vary from less than a second to several minutes, shorter contact times resulting in less complete isomerization while longer contact times favor undesirable side reactions. Under conditions of pressure and temperature favorable to the isomerization of normal olefines, there is no appreciable isomerization of aliphatic and alicyclic hydrocarbons.

The extent of isomerization produced will depend on the desired composition of the cracked products. If the maximum possible yield of pentadienes is desired, isomerization will be conducted until equilibrium is substantially reached. If it is desired to increase the yield of pentadienes without reaching its maximum, the isomerization will be conducted so as to isomerize the straight chain olefines only partially.

A change in the degree of isomerization may be caused by changing the catalyst or by by-passing

part of the feed, but is preferably obtained by lowering the temperature of isomerization or decreasing the contact time, or by a combination of these methods.

5 The degree of isomerization of a normal olefinic feed may be determined by any of the standard methods, for example, by the change produced in its octane rating since it is well known that the branching of carbon chains increases the octane number of hydrocarbons.

10 Another indication of the extent of isomerization is obtained by the relative proportion of C₄ and C₅ hydrocarbons in the cracked products. Isomerization decreases this proportion, i. e. isomerized olefines yield on cracking a relatively larger amount of C₅ hydrocarbons in the C₄—C₅ cut.

15 Thus the degree of isomerization may be measured, regulated, and controlled by the relative ratio of butadiene and pentadiene, or of C₄ and C₅ hydrocarbons produced by cracking, or by the octane number of the isomerized olefines, or by other suitable indices.

20 The first two methods or any other based upon the properties of the cracked products are preferable as they allow compensation for irregularities of the feed by varying the degree of isomerization so as to maintain a steady production.

25 The vapor phase cracking step of this process is conducted so as to gasify 15% to 85% of the feed per pass. We define as gasified that part of the cracked products which consists of molecules having less than six carbon atoms. The cracking temperature, i. e., the maximum temperature to which the cracking stock is heated, is above 500° C., preferably 650° C. to 850° C.

30 The cracking is conducted advantageously at pressures of about atmospheric or below, and preferably not substantially above 100 to 150 p. s. i. Thus, pressures above atmospheric sufficient to overcome the resistance of conduits, condensers, and other equipment which follow the cracking zone may be maintained therein. If desired, the cracking may be conducted in the presence of steam, nitrogen and other substantially inert gases and the concentration of such gases may vary from traces up to 95 mol per cent of the mixture.

35 The heating of the hydrocarbons to the cracking temperature may be achieved by contact with a heated surface, for example in an externally heated coil, or in a preheated brick checker work, or by admixture of hot, substantially inert gases, or by a combination of these methods. The rate of heating should be as high as possible to avoid undesirable side reactions at the intermediate temperatures. In order to avoid destruction of dienes formed in the cracking, the cracked product should be quenched rapidly from the cracking temperature down to safe temperatures, preferably below about 400° C.

40 In order to prevent excessive coke formation in the cracking zone, it is often preferred that this zone be constructed of non-ferrous metals or alloys containing less than predominating amounts of iron. Materials which do not cause rapid coke formation such as copper-containing alloys, e. g., aluminum- or phosphor-bronze, or refractory ceramics, are thus preferred in the construction of surfaces which are exposed to hydrocarbons at cracking temperatures.

45 Cracking according to this invention is preferably purely thermal, i. e. non-catalytic, and is conducted in the absence of catalyst, be it added catalysts such as gaseous halogenated

compounds, solid catalytic metals or oxides, or catalysts preformed in situ, e. g. lustrous carbon or pyrophoric metals.

The velocity at which the vapors pass through the cracking zone depends on the exact result desired, the temperature and pressure of cracking, and the dimensions of the cracking zone. The space velocity necessary to produce a given degree of gasification increases rapidly as the cracking temperature is raised. The real velocity of the gaseous hydrocarbons in the cracking zone is very difficult to determine accurately, because the volume of the cracking stock changes rapidly under the cracking conditions. Therefore, in defining this invention, we prefer to utilize the concept of liquid space velocity which is the liquid volume of the feed delivered to the cracking zone per volume of said zone per hour. The cracking zone is defined as the space occupied by gas in which the temperature is within 20° C. of the maximum cracking temperature. Liquid space velocity can be accurately measured, and, for a given pressure, temperature, and dilution, determines the real space velocity of the vapors.

The cracked products thus obtained comprise dienes as well as many other gaseous and liquid hydrocarbons. These products may be withdrawn, treated, separated and used as may be desired but it is advantageous to prepare and utilize certain portions thereof as follows.

The cracked products are subjected to fractional distillation to produce a light gaseous fraction substantially free of C₄ and heavier; a C₄—C₅ fraction rich in and containing substantially all the buta- and penta-dienes; a cracked naphtha or a middle oil fraction or both; and tars.

The first and last of these fractions, i. e. diene-free gases and tars, are preferably withdrawn. The C₄—C₅ fraction is treated to separate therefrom the dienes by conventional methods.

The cracked naphtha has a composition varying with the intensity of the cracking, i. e., it may substantially retain the composition of the cracking feed, or it may have become more or less aromatic.

If the cracking is relatively superficial, i. e., the gasification per pass is of the order of 25%, for example, 15% to 40% and preferably 20% to 30%, the ungasified portion of the cracking stock is still predominantly composed of mono-olefines. It is advantageously re-cracked and treated like the original cracking stock, for example by re-circulation as part of said stock.

If the cracking is deep, i. e., the gasification is of the order of 65%, for example 50% to 85%, and preferably 60% to 70%, the naphtha fraction of the cracked products may contain substantial amounts of aromatic hydrocarbons which apparently are formed by secondary reactions such as polymerization or condensation of the primary products. In this case, it is advantageous to separate valuable aromatic hydrocarbons such as benzene, toluene, styrene, etc., from the naphtha fraction and, if desired, to further crack the remaining mono-olefines. This latter procedure, i. e., the deep cracking, is often preferable because the cracking yields in the gaseous products per pass higher amounts of diolefines and, simultaneously, liquid products which are valuable per se. However, if it is not desirable to recover aromatics, the former procedure, i. e., superficial cracking, is often preferable.

The cracking may also be conducted for intermediate gasification such as about 40% to 75

50%, but this is in general less desirable as it produces aromatics in small though appreciable amounts which are sufficiently large to be objectionable in cracking, yet not large enough to make their recovery desirable.

The naphtha fraction may also contain poly-olefines having six and more carbon atoms. These hydrocarbons may be desirable in themselves. On the other hand, they may interfere, for example, in the cracking because of their tendency to polymerize, or in the recovery of aromatics with the aid of selective solvents because of their solubility therein which comes close to that of aromatics. It is thus often desirable to separate and eliminate them.

Our process is illustrated in the accompanying drawing which represents a simplified flow diagram of an embodiment of this invention.

For simplicity, the drawing does not show pumps, tanks, heat exchangers, valves, by-passes, vents, reboilers, condensers, coolers, and other auxiliaries, the proper placement of which will be at once evident to those skilled in the art.

A paraffinic hydrocarbon mixture is introduced from storage, not shown, into zone 1, wherein a distillate oil rich in normal mono-olefines is prepared and withdrawn through line 2. The preparation of these mono-olefines in zone 1 may be conducted substantially as described in the above-mentioned Van Peski U. S. Patent No. 2,172,228. Oils rich in, e. g., comprising 50% or more of, normal mono-olefines may also be produced in any other suitable manner and be admitted from a source not shown through line 3, which joins line 2.

The mixed fluids are led through line 2 into isomerization zone 4 wherein they are treated under isomerizing conditions in the presence of a suitable catalyst. This isomerization may be conducted substantially as described in the above-mentioned Han Hoog, U. S. Patent No. 2,217,252. The degree of isomerization may be controlled by regulating the temperature of jacket 5. This temperature may, for example, be regulated by suitable means not shown, so as to produce a most convenient or desirable proportion of butadiene and pentadienes. Lowering the temperature of zone 4 reduces the extent of isomerization and increases the yield and proportion of butadiene, while increasing this temperature increases the isomerization, thereby raising the yield and proportion of pentadienes.

The isomerized or partially isomerized olefines are obtained through line 6. Suitable recycle stock obtained in the process as hereinafter described may be preferably admitted through line 8 and commingled therewith.

The mixed fluids, preferably in vapor form, are led through line 6 into cracking coil 7 in furnace 8 in which the desired conditions of temperature, pressure, and residence time are maintained, for example at 700° C., atmospheric pressure, and a liquid space velocity of about 150, so as to effect a gasification of about 25%.

The cracked products which leave reaction coil 7 through line 11 are quenched with suitable quenching fluid introduced through line 12 from a source not shown, and are separated from tars and other relatively heavy materials in fractional distillation column 13. The lighter products, including gases and naphtha, are taken overhead through vapor line 15. The heavier products are withdrawn from the system through line 17.

The products in line 15 pass into stabilizer 19.

wherein an overhead fraction consisting essentially of C₅ and lighter components is separated from a heavier naphtha fraction; the latter, substantially free of C₅ and lighter components, is taken through line 24 and may go through line 25 to storage not shown, or preferably may serve as recycle stock which is returned through lines 25, 8 and 6 to the cracking coil 7. If the cracking stock is composed of hydrocarbons substantially heavier than C₅, it is advantageous to also eliminate from the recycle stock those components formed during cracking which are lighter than the original cracking stock. This can be done by withdrawing an appropriate side stream from fractionator 19 through line 26.

If desired, the polyolefines contained in this naphtha fraction may be separated in zone 27, for example, by extraction with a suitable complex-forming reagent, e. g., Cu₂Cl₄, AgCl, SO₂, etc., or by polymerization with or without suitable catalysts such as poly-oxy acids, e. g., H₂SO₄, H₃PO₄, etc., or Friedel-Crafts catalysts, or by the Diels-Alder reaction involving the use of maleic anhydride-type reagents, etc.

The overhead C₅ and lighter fraction from stabilizer 19 is taken through conduit 29 to a fractionating system wherein it is subjected repeatedly to fractional distillation. In column 31 a bottom fraction is produced comprising predominantly hydrocarbons having five carbon atoms, which is taken through line 33, and a lighter fraction substantially free from C₅ components. The latter is taken overhead through line 35 to fractionator 37, where a bottom fraction comprising predominantly hydrocarbons having four carbon atoms is produced and withdrawn through line 39. Remaining gases substantially free from C₄ and heavier components are withdrawn overhead through line 41.

Thus, separate C₅ and C₄ fractions are taken through lines 41 and 39, respectively.

The C₄ fraction which contains butadiene is led through line 39 to column 43, wherein it is subjected to extractive distillation with a suitable solvent having a relatively high boiling range and greater solvent power for butadiene than for butylenes and butanes. This liquid is supplied to the top of extractor 43 through line 45 and is contacted with the ascending C₄ vapors so as to produce a "fat" solvent charged with substantially pure butadiene. This "fat" solvent is eliminated from the bottom of the column 43 through line 47. This "fat" liquid is separated by fractional distillation in fractionator 49 into the "lean" solvent and butadiene. The butadiene so produced is withdrawn through overhead line 51 while the "lean" solvent is drawn off at the bottom through line 45 and is returned to extractor 43. The butylenes and butanes separated from the butadiene in column 43 are withdrawn through line 53. The large proportion of olefines in this fraction makes it valuable for the manufacture of polymer or alkylate gasoline.

The C₅ fraction, rich in pentadiene, is given a treatment similar to that of the C₄ fraction. Line 53 leads it to column 55, wherein it is extracted in the vapor phase by a lean solvent supplied through line 51. The resulting fat solvent is drawn off through line 52, and the residual pentanes and amylanes are withdrawn through line 54. The fat solvent is fractionally distilled in fractionator 43 to isolate pentadienes which are withdrawn through line 65, while the lean solvent is recirculated through line 51.

Suitable solvents for the vapor phase extrac-

tion of dienes include, for example, alcohols such as butyl alcohols, amyl alcohols, cyclohexanol, etc.; aldehydes such as furfural, or benzaldehyde, etc.; ketones such as acetone, methyl ethyl ketone, methyl propyl ketone, acetophenone, cyclohexanone; ethers such as di-isopropyl ether, dichloroethyl ether, dioxane; organic nitrogen bases such as aniline, toluidine, phenyl hydrazine, ethylene diamine, ethanol diamine; phenols such as phenol, cresol, xylenols; esters such as ethylene chlorhydrin, dimethyl phthalate, diethyl tartrate, ethylene dichloride, lactic acid nitrile, acetonitrile, di-isopropyl or allyl sulfate, ethyl borate or ethyl orthosilicate; other organic derivatives of mineral acids such as nitrobenzene, nitromethane, nitroethane, and many other polar compounds.

The recovered pentadienes usually comprise a mixture of isoprene (2-methyl butadiene), piperylene (n-pentadiene) and cyclopentadiene. This mixture may be either withdrawn through line 67 or, if desired, may be further fractionated to separate the several C₅ dienes from one another by leading it through line 69 to zone 11, where the cyclopentadiene is dimerized by subjecting the mixture to moderate heat in the liquid phase. The resulting product is fractionally distilled, the dimer forming the distillation residue which is taken through line 73 to be withdrawn through line 75, or to be regenerated by exposure to high temperature and vacuum in a depolymerizing zone 19, to which line 11 leads. The vapors of the acyclic pentadienes are removed from the dimerization zone 11 through line 81, and may be further separated in fractionator 83 to produce isoprene which is taken overhead through line 85 and piperylene, which is obtained at the bottom, through line 87.

The process as illustrated in the drawing can also be carried out in a different manner if desired. The cracking in coil 7 may be intensified, for example, by reducing the space velocity to about 40 under the same conditions of pressure and temperature, so as to obtain a gasification of about 65%. The naphtha fraction produced under these circumstances and taken through line 21 from fractionator 19 contains aromatic hydrocarbons.

These valuable hydrocarbons may be separated and the recycle stock recovered by convenient methods, such as fractional and extractive distillation, or liquid-liquid extraction, or both. For example, the liquid withdrawn through line 21 is led through line 89 and preferably through zone 27, where it is freed of polyolefines, to fractionator 91 wherein it is split into a narrow C₆ overhead fraction taken through line 93 and a bottom fraction of C₇ and heavier components withdrawn through line 95. This line leads to fractionator 97, wherein another narrow C₇ overhead fraction is separated and taken through line 99, and a bottom fraction substantially free from C₇ hydrocarbons which is withdrawn through line 101, either to be discarded or further treated as will be described.

The C₆ and C₇ fractions thus separated are rich in benzene and toluene, respectively.

The C₆ fraction is conducted through line 93 to column 103 wherein it is subjected to extractive distillation with a lean selective solvent for aromatics introduced through pipe 105. The fat solvent rich in benzene leaves through line 107 and the residual C₆ hydrocarbons are withdrawn overhead through line 109 or may be returned to the cracking coil 7 through lines 25, 8 and 6. The

fat solvent is fractionally distilled in fractionator 111 so that the lean solvent is recovered as the bottom fraction and returned through line 105 to extractor 103, and the benzene is obtained overhead through line 113.

The gaseous C₇ fraction is conducted through line 88 to column 115 wherein it is extracted with a lean solvent for aromatics introduced through line 117. The fat solvent rich in toluene leaves through line 119, and the residual C₇ hydrocarbons are withdrawn overhead through line 121 and may be returned to the cracking coil 7 through lines 25 and 8. The fat solvent is fractionated in fractionator 123, so that the lean solvent is recovered as the bottom fraction and is returned through line 117 to extractor 115. The toluene is obtained overhead through line 125.

Suitable solvents for the recovery of aromatics by extractive distillation are, for example, phenol, cresylic acids, alkyl phenol mixtures, aniline, alkyl anilines, diphenyl amine, ditolyl amines, carbitols (diethylene glycol mono-ethers) such as methyl, ethyl, and propyl carbitols, chlorinated dialkyl ethers such as beta-beta-dichlorethyl ether, nitrobenzene, nitrotoluene, nitroxylenes, naphthols, alkyl naphthols, benzo phenone, phenyl tolyl ketone, diphenyl ketone, alkyl phthalates such as dimethyl phthalate, alkyl salicylates such as methyl salicylate, benzyl alcohol, benz chlorides; i. e., benzyl, benzal, and benzo chlorides, benzonitrile, diphenyl oxide, ditolyl oxide, hydroxy pyridine, nitropyridine, chlorinated pyridines, quinoline, isoquinoline, chlorinated quinoline, hydroxy quinolines, 5-nitro quinoline, tetrahydrofurfuryl alcohol, furfural alcohol, furfural, the mono glycerol ethers, such as 1-methoxy glycerol, 2-methoxy glycerol, 1-ethoxy glycerol, 2-ethoxy glycerol, 1-propoxy glycerol, 2-propoxy glycerol, 1-isopropoxy glycerol, 2-isopropoxy glycerol; the glycerol diethers such as 1,2-dimethoxy glycerol, 1,3-dimethoxy glycerol, 1,2-diethoxy glycerol, 1,3-diethoxy glycerol, 1,2-dipropoxy glycerol, 1,3-dipropoxy glycerol, 1,2-di-isopropoxy glycerol, and 1,3-di-isopropoxy glycerol; the mixed diglycerol ether esters such as 1-ethoxy, 2-methoxy glycerol, 1-methoxy, 3-propoxy glycerol, and 1-ethoxy, 2-isopropoxy glycerol.

The heavier-than-C₇ bottom fraction from fractionator 97 obtained through line 101 contains aromatics. The latter are preferably separated by liquid-liquid extraction with a liquid having greater solvent power for aromatics than for olefinic hydrocarbons, for example liquid SO₂. For this purpose, the hydrocarbon liquid is delivered through line 101 to extractor 126 wherein it is extracted with liquid SO₂ entering through conduit 128. The raffinate passes through line 130 to a stripper 132 wherein it is stripped of dissolved SO₂ and thence is preferably returned to the cracking coil 7 through lines 134, 8 and 6. The extract containing aromatics is conveyed from extractor 126 through line 136 into separator 138 wherein a bottom fraction comprising mainly SO₂-free aromatics and an overhead fraction of SO₂ are produced. The aromatics are obtained through conduit 140 while the SO₂ is taken overhead through line 142 to be liquefied in cooler 144 together with the SO₂ taken from stripper 132 through line 146. The liquefied SO₂ is then reintroduced through conduit 128 into extractor 126.

Other solvents suitable for the liquid-liquid extraction are, for example, nitrobenzene, methyl acetate, phenyl acetate, methyl or ethyl cellosolve, furfural, acetone, aniline, phenol, cresylic

acids, dichlorethyl ether, antimony trichloride, SO₂ benzene mixtures, or combinations of solvents and anti-solvents such as phenol or cresol with propane, etc.

If desired, the charge in line 88 may by-pass the fractionators 91 and 97 through a by-pass not shown and all the aromatics separated by liquid-liquid extraction in extractor 126, as described; or, alternatively, if desired, the liquid-liquid extraction step may be replaced by further fractional and extractive distillation of the several fractions.

The separation of buta- and pentadienes may be conducted as described above by extractive distillation or other vapor phase extraction with similar solvents; or by azeotropical distillation in the presence of anhydrous ammonia, methylamine, CO₂, lower alcohols, etc.; or by liquid-liquid extraction with acetone, furfural, aniline, phenol, etc.; or through formation of complex compounds with copper or silver salts, SO₂, etc.; or by polymerization under the influence of heat, pressure, light, or catalysts such as Na, K, H₂SO₄, H₃PO₄, P₂O₅, AlCl₃, etc.; or a combination thereof.

It may sometimes be preferred to separate the dienes or the aromatics, or both, without pre-fractionation or following a degree of fractionation less thorough than described. Alternatively, it may also sometimes be desirable to produce a sharper fractionation before further recovery, or to use directly fractions rich in dienes or aromatics, or both, produced by very sharp fractionation.

The following examples illustrate this process:

Example I

A normal olefine distillate was obtained by cracking wax in the vapor phase at about 560° C. The boiling range of the distillate used was from 160° C. to 220° C., its specific gravity 0.7710, refractive index at 20° C. for line D, 1.4357, bromine number 74 and average molecular weight 152. Part of this cut was isomerized over "Nalco No. 300" catalyst composed mainly of silicon, magnesium, aluminum and oxygen at a temperature of 472° C. to 480° C. and at a liquid space velocity of 5 volumes of olefines per volume of catalyst.

Both olefinic stocks, i. e., the unisomerized and the isomerized, were cracked at a temperature of 750° C. in a phosphor-bronze tube filled with quartz chips and the cracked products analyzed. The following table shows the results obtained.

	Unisomerized	Isomerized
Liquid space velocity.....	128	148
Gasification..... percent	67	59
Composition of the gas phase:		
H ₂ ..... weight percent	0.3	0.2
CH ₄ ..... do	7.0	7.2
C ₂ H ₄ ..... do	29.6	8.7
C ₂ H ₆ ..... do	4.5	3.0
C ₃ H ₈ ..... do	22.2	13.3
C ₄ H ₁₀ ..... do	1.2	0.6
C ₄ H ₈ butadiene..... do	9.6	4.9
Iso-C ₄ H ₈ ..... do	0.9	11.6
nC ₄ H ₁₀ ..... do	11.6	14.2
C ₅ H ₁₀ ..... do	0.2	3.2
C ₅ H ₈ pentadiene..... do	3.9	8.7
C ₆ H ₁₀ ..... do	8.7	22.8
C ₇ H ₁₆ ..... do	0.9	5.1
Total dienes.....	13.5	13.6
Ratio C ₄ dienes/C ₅ dienes.....	2.46	0.56

It will be noted that the isomerization not only modified the proportion of pentadienes, but also increased the yield of iso-olefines and of higher olefines.

While the process of the present invention is hereinabove described with special reference to

normal olefins for which it is particularly useful and suitable, the principle of isomerizing may be applied with proper variations to other cracking feeds such as, for example, waxes and other hydrocarbons which predominate in straight chain molecules or naphthenic fractions containing cyclopentane derivatives. In the case of straight chain hydrocarbons isomerization is conducted to produce a branching, while in the case of naphthenes it is conducted to convert five-membered to six-membered rings, in both cases resulting in an improvement in the diolefine yield.

We claim as our invention:

1. An improved process for the production of dienes from normal mono olefins containing from 6 to 12 carbon atoms to increase the proportion of C₅ dienes comprising the steps of isomerizing said mono olefins to produce branched chain olefins, non-catalytically cracking the isomerized product in the vapor phase at a temperature between 650 and 850° C. and at a pressure below about 150 p. s. i. for a time to gasify 15 to 85 per cent thereof to produce dienes, separating C₄ and C₅ dienes from the resulting cracked product, separating from the resulting cracked product a fraction having a boiling range substantially the same as the isomerized product, removing aromatics and dienes from said fraction and recycling the resultant diene-free and aromatic-free product to said cracking step to produce more dienes.

2. An improved process for the production of dienes from a fraction of normal mono-olefins having 6 to 12 carbon atoms to increase the proportion of pentadienes, comprising the steps of isomerizing said fraction of normal mono-olefin

5 in the presence of activated alumina to produce branched chain olefins, non-catalytically cracking the isomerized product in the vapor phase at a temperature between 650° C. and 850° C. and at a pressure below about 150 p. s. i. for a time to gasify 15 to 85% thereof to produce dienes, fractionating the cracked products to form a light fraction of hydrocarbons having not more than 6 carbon atoms and a heavier fraction

10 having the same boiling range as said isomerized product, removing C₄ and C₅ dienes from said light fraction, selectively removing polyolefins from said heavier fraction, solvent extracting with liquid sulfur dioxide the resulting polyolefin-free heavier fraction, and recycling the resulting aromatic-free and polyolefin-free cracked products to said cracking step to produce more dienes.

15 3. An improved process for manufacturing dienes from a hydrocarbon distillate predominating in normal mono-olefins having 6 to 12 carbon atoms whereby the proportion of pentadienes obtained is increased, comprising the steps of isomerizing said distillate to produce branched chain olefins, non-catalytically cracking in the vapor phase at a temperature between 650° C. and 850° C. and at a pressure below about 150 p. s. i. a normally liquid mixture of said isomerized product and a recycle oil produced in the process for a time to gasify 15 to 85% thereof to produce dienes, separating from the resulting cracked products at least the following fractions: a diene fraction, said recycle oil which is substantially free of tarry aromatics and normally gaseous components, and a tarry fraction.
